HYDRAULIC LIFTER

Raymond M. Ulrich, Roanoke, Ill.

Application August 23, 1947, Serial No. 141,035

Term of patent 14 years

(Cl. D41—1)

To all whom it may concern:

Be it known that I, Raymond M. Ulrich, a citizen of the United States, residing at Roanoke, in the county of Woodford and State of Illinois, have invented a new, original, and ornamental Design for Hydraulic Lifter, of which the following is a specification, reference being had to the accompanying drawing, forming part thereof.

Figure 1 is a side view of a hydraulic lifter, showing my new design;

Figure 2 is an end view; and

Figure 3 is a perspective view of the lifter in maximum raised position.

The dominant features of my design reside in the portion shown in full lines.

I claim:

The ornamental design for a hydraulic lifter, as shown and described.

RAYMOND M. ULRICH.
